UNITED STATES PATENT OFFICE.

JAMES BARLOW AND JAMES MOSES, OF TRENTON, NEW JERSEY, ASSIGNEES
TO THE MERCER POTTERY COMPANY, OF SAME PLACE.

DESIGN FOR A DINNER OR TEA SET.

SPECIFICATION forming part of Design No. 14,808, dated February 26, 1884.

Application filed February 28, 1883. Term of patent 7 years.

To all whom it may concern:

Be it known that we, JAMES BARLOW and JAMES MOSES, of Trenton, in the county of Mercer and State of New Jersey, have invented a new and original Design for Sets of China-Ware, particularly Dinner, Tea, and Toilet Sets, of which the following is a full, clear, and exact description, reference being had to the accompanying drawings, which form a part of this specification.

Our invention relates to a new and ornamental design for such sets; and in the drawings accompanying and forming a part of this specification, Figure 1 shows a covered dish embodying our design, and Fig. 2 shows a cover of such dish, and Fig. 3 shows a tea-pot, all parts of such sets and all embodying our design.

While the drawings show the dish and tea-pot only, our design can be applied, and we do apply it, to all the articles contained in such sets.

In Fig. 1, A represents the cover of the dish; B, the body of such dish; C C C, the handles of such dish and cover, and D the feet. The body of the dish is made with nearly straight-lined sides, widening from the bead at the bottom upward until near the top of the side, where there is a sudden and slight contraction surmounted by a straight-lined neck, K, also widening toward the top in equal degree with the sides. At the bottom of the sides is the bead B', below which are the feet D, connected by the ornamental curtain D'. The cover, of which a top view is given in Fig. 2, has the ornamentally-outlined edge part E, within which part it rises pyramidalistically until it reaches the plane F, rising slightly above the cover. Upon this plane F is affixed

the handles C. The sides of the cover, as they rise within the edge part E, are not straight-lined, but, as shown in Fig. 2, swelled slightly at the center. This is also the case with the sides of the body B. The handles are constructed with the bosses C', curved rib C', and ornamental ends C', as shown in Fig. 3. In vessels where the neck K projects above the cover, as shown in Fig. 3, we preferably es- callop said neck to correspond with the curtain D'.

What we claim as our invention is—

1. A design for a dish, consisting of the body B, such body provided with a bead and with feet connected together by an ornamental curtain, and also provided with the ornamental handles C, all substantially as shown and de- scribed.

2. A design for a dish, consisting of the body B, provided with a bead and the ornamental handles C, and with the feet D, connected by the ornamental curtain D', and surmounted by the ornamental cover, all substantially as shown and described.

3. A design for a dish-cover, of the outline shape shown, surmounted by pyramidal sides, such pyramidal sides not ending in an apex, but surmounted by a plane slightly rising therefrom, and provided with the ornamental handles C, all substantially as shown and described.

4. The design for handles for dinner, tea, and toilet sets, substantially as shown.

JAMES BARLOW.

JAMES MOSES.
